CLAIM

The ornamental design for a electronic visual display with graphical user interface for physics status and operations, as shown and described.

DESCRIPTION

FIG. 1 is a front view of an electronic visual display with graphical user interface for physics status and operations; FIG. 2 is a front view of a second embodiment thereof; and, FIG. 3 is a front view of a third embodiment thereof. The outer broken lines showing the electronic visual display forms no part of the claimed designed. The remaining broken lines showing text and portions of the graphical user interface form no part of the claimed design.
